(57) **CLAIM**

The ornamental design for an audio component front face, as shown and described.

DESCRIPTION

FIG. 1 is a perspective view of an audio component front face showing our new design;

FIG. 2 is a front elevational view thereof;

FIG. 3 is a side elevational view of one side thereof;

FIG. 4 is a side elevational view of the other side thereof;

FIG. 5 is a top plan view thereof; and,

FIG. 6 is a bottom plan view thereof.

The rear side is not claimed. The broken line showings of the circles are for illustrative purposes only and form no part of the claimed design.
